UNITED STATES PATENT OFFICE.

JAMES L. SHUTE, OF SEATTLE, WASHINGTON.

WATERING-TROUGH FOR FOWLS.

1,127,296.

Specification of Letters Patent.

Patented Feb. 2, 1915.

Application filed June 29, 1914. Serial No. 848,052.

To all whom it may concern:

Be it known that I, JAMES L. SHUTE, a citizen of the United States, residing at Seattle, in the county of King and State of Washington, have invented certain new and useful Improvements in Watering-Troughs for Fowls; and I do hereby declare the following to be a full, clear, and exact description of the invention, such as will enable others skilled in the art to which it appertains to make and use the same.

This invention relates to animal husbandry, and more especially to watering fountains and troughs; and the object of the same is to produce a trough of this kind which has means for excluding the smaller fowls therefrom.

To this end the invention consists essentially in a peculiar form of partition and its divisional wings, the whole being removably inserted in the trough so that it may be withdrawn for cleaning the parts; and the invention further consists in details as will be elaborated in the following specification and claims.

In the drawings Figure 1 is a side elevation of this device complete, partly in section, Fig. 2 is a perspective detail of one end of the partition, and Fig. 3 a sectional detail on about the line 3—3 of Fig. 1. Fig. 4 is a plan view of a portion of the blank from which the partition is made, showing how the wings are cut. Fig. 5 is a perspective detail of part of a similar partition made of sheet metal.

This watering device is of that class which employs an inverted bottle as its fountain F. The bottle is inserted in the upper end of an upright reservoir 1 which, with the parts that follow, is made of metal and by preference of galvanized metal so that it will not rust. The reservoir 1 is shown as cylindrical in contour, open at its top and closed at its bottom, and within this reservoir may be inserted a rest composed of crossed strips 2. A wire 3 passes through the cork C and is long enough to pass through the neck of the bottle F when the cork is in place. When a filled bottle is inverted and put into the reservoir 1, the wire strikes the bottom of the latter and pushes the cork out of the bottle neck so that it rises in the water within the bottle, floats thereon and falls therewith, and when the fountain is removed for replenishing its charge

the cork is actuated to hold said charge therein by pulling on the wire.

Secured in a water tight manner to and projecting radially from one side of the reservoir is a trough 4 which preferably has a flat bottom standing flush with the bottom of the reservoir, and parallel upright sides about two inches high, its inner end communicating with the interior of the reservoir through an inlet hole 5 and its outer end 6 being closed as shown, or in some instances provided with an outlet 7 where some other form of feed than the fountain is provided and where the water is to run continuously through this trough. The trough is preferably of galvanized iron, with the upper edges of its side and end walls beaded as at 8, in width it is about two inches, and in length it is proportioned to the size of the fountain or volume of the feed and the number of fowls such as chicks or ducks which are to be watered.

I find by experience that when a watering trough is in use by brooder ducks or day old chicks they frequently suffer and are often killed by getting into the water, splashing it onto themselves and each other to too great an extent, or crowding themselves into the trough or against each other. This I overcome by the use of a partition made of galvanized wire screening of about a quarter inch mesh, the partition having lateral wings at proper intervals, all as best seen in Figs. 1 to 4. I may here say that for older fowls the partition 10 shown in Fig. 5 may be substituted, this partition being of sheet iron or tin and the wings 11 of the same material and the false bottom omitted. Either partition is readily removable from the trough so that all parts can be cleansed and perhaps boiled.

The wire screen partition preferably employed is cut from a sheet 12 of screen fabric, one end of which is shown in Fig. 4 wherein the full lines indicate cuts and the dotted lines indicate subsequent bending. This sheet will be of the same length as the trough, and of a width to enable it to be folded into the shape shown in Fig. 2. The blank is cut on the lines 13 and 14 to produce wings 15 and 16 whose fold lines 17 and 18 are in alinement whereas the bodies of the wings are staggered. The result of this cutting of the blank is that when the wings are opened outward as

shown at 16 in Fig. 2, the holes or openings 19 and 20 are out of register with each other. The entire sheet is bent on a central longitudinal line 21 into two sides or leaves 22, and the leaves are bent outward at right angles on lines 23 into a two-part false bottom 24, the combined width of the parts being the same as the internal width of the trough. Finally the parts of the bottom are bent down on lines 25 into upright flanges 26 which contact with the inner faces of the side walls of the trough and whose lower edges 27 rest on the bottom of the trough when this structure is in place. The height of said flanges is such that the false bottom 24 underlies the lower edges of the outbent wings 15 and 16 and stands a little below the level of the water in the trough, whereas the wings rise to a point considerably above the level of the water and above the sides of the trough, and these wings are obviously for the purpose of preventing the fowls from crowding each other. The leaves 22 rise above the wings, and their connecting bend 21 may be covered and reinforced by beading 28 of any suitable character, the same preferably also extending down the ends of the partition at 29 and terminating at the false bottom.

The structure shown in Fig. 5 should have the same dimensions so that it is interchangeable with the reticulate partition for the purposes above described, but the solid partition has no false bottom and needs none as it is used with older chicks or ducks and with adult fowls who may be permitted to put their bills into the water as far as they like. It is quite possible that the wings of this partition could be set a little farther apart, or perhaps their every other wing omitted. But these details as well as other details not elaborated herein, may be left to the manufacturer. I emphasize the removability and interchangeability of parts, first because it permits cleansing, and second because it adapts the device to various fowls or various sizes of fowls.

Copies of this patent may be obtained for five cents each, by addressing the "Commissioner of Patents, Washington, D. C."

What is claimed is:

50

1. In a watering device, the combination with a rectangular trough, and means for feeding water to one end thereof; of a removable upright partition extending along the center of the trough, and a series of 55 upright transverse wings projecting outward from the partition into contact with the side walls of the trough and extending from lines coincident with the lower edge of the partition to points above the upper 60 edges of said side walls, for the purpose set forth.

2. A partition for watering troughs formed of sheet material folded on a central line into contacting upright leaves and 65 bent outward from the lower edges of said leaves into a bottom, said leaves having wings cut from them at points out of register with each other, and the wings bent outward over the bottom and at angles to 70 the leaves, for the purpose described.

3. A partition for watering troughs formed of a sheet of reticulate material folded on a central line into contacting upright leaves, bent outward from the lower 75 edges of said leaves into a two-part false bottom, and the parts of said false bottom bent downward at their outer edges into upright flanges.

4. A partition for watering troughs 80 formed of a sheet of reticulate material folded on a central line into contacting upright leaves, bent outward from the lower edges of said leaves into a two-part false bottom, and the parts of said bottom bent 85 downward at their outer edges into upright flanges; said leaves having wings cut from them at points out of register with each other, and the wings bent outward at right angles to the leaves, for the purpose 90 described.

In testimony whereof I affix my signature in presence of two witnesses.

JAMES L. SHUTE.
